HEAD MOUNTED FLASHLIGHT

Angelo Castellano, 2320 Spruce St.,
Tampa, Fla. 33607

Filed July 17, 1967, Ser. No. 7,843

Term of patent 14 years

(Cl. D48—24)

The single figure is a perspective view of head mounted flashlight embodying my new design.

The dominant features of my design reside in the portions shown in full lines.

I claim:

The ornamental design for a head mounted flashlight, as shown and described.
